A. E. LANE

LID SUPPORT

Filed Aug. 20, 1925

Fig. 3.

UNITED STATES PATENT OFFICE.

ALBERT E. LANE, OF MANTUA, NEW JERSEY, ASSIGNOR TO VICTOR TALKING MACHINE COMPANY, A CORPORATION OF NEW JERSEY.

LID SUPPORT.

Application filed August 20, 1925. Serial No. 51,496.

This invention relates to a support for maintaining a movable member at a certain position of adjustment relative to a supporting body, and more particularly to a lid support of the type disclosed in the applications of Armer P. Luker, Serial No. 51,455, filed Aug. 20, 1925, and Samuel H. Wismer, Serial No. 51,488, filed Aug. 20, 1925.

An object of the present invention is to provide a lid support of the type disclosed in the above-named applications which embodies the advantages of these former devices and which possesses additional advantages in construction and economy of manufacture.

More particularly, an object of the present invention is to provide a one-hand lid support that includes novel means for yieldingly maintaining the lid or movable member in at least one position of adjustment.

A further object is to provide a single member for increasing frictional engagement between the movable and stationary elements and to constitute means for yieldingly maintaining the lid or cover in at least one adjusted position.

The invention will be readily understood by reference to the accompanying drawings illustrating one embodiment of the invention that is particularly adapted for use in talking machine cabinets. It is to be expressly understood, however, that the structure of the present invention is adapted for use in other combinations and is not limited to the particular combination illustrated in the drawings, wherein,

Fig. 1 is a side elevation, with parts broken away, illustrating one embodiment of the present invention installed in a talking machine cabinet;

Fig. 2 is a sectional end view taken on the line 2—2 of Fig. 1, the cabinet lid being shown in closed position; and

Fig. 3 is an enlarged detail sectional view taken on the line 3—3 of Fig. 1.

Referring to the drawings wherein like reference characters refer to like parts throughout the several views, 1 represents a supporting body, as for example a cabinet of a talking machine, and 2 the lid or cover which is movably secured in any suitable manner to the body 1 as by means of the usual hinges. Attached to the supporting body 1, or to the member 2, at any desired

point, but preferably to the inner surface 55 of the body 1, is an elongated plate 3 which carries on its inner surface a channel bar 4. In the form shown, plate 3 and the U-shaped channel bar 4 are mounted so that the latter extends into a recess 5 formed in the inner 60 surface of the body 1, but it will be understood that this is not essential as the bar 4 may be mounted on the outer surface of plate 3 or spacing washers may be employed between this plate and the body 1. 65 To facilitate the mounting of the plate 3 a strip 6, formed of any suitable material, such as wood, may be interposed between the plate 3 and body 1 for receiving screws 7 or other suitable retaining members which extend through openings in the plate and into the body 1. The channel bar 4, which may be secured to the plate 3 in any suitable manner, is preferably provided with a longitudinal slot 4^a which registers with a similar 70 slot 3^a formed in the plate 3. The lower side 4^b of the channel bar 4 is cut away at the opposite ends thereof, as at 4^c, Fig. 1, for a purpose to be described hereinafter.

Slidably mounted between the upper and lower walls of the channel bar 4, is a block 8 which may be rectangular in shape and which is held in place between the walls by means of a pivot member 9 that is provided on its inner end with a washer 9^a which is held in place by the upset end 9^b of the pivot pin 9. Loosely mounted on the outer end of the pin is a link 10 which is held in position by means of the outer head 9^c of the pivot pin and a washer 11 that is interposed between said link and the plate 3. The upper end of the link 10 is pivotally secured to an angle bracket 12 of any suitable form that is attached to the inner surface of lid 2 as by means of screws 13.

Resilient means are provided for increasing frictional engagement between the block 8 and the walls of the channel bar 4, and also for resiliently maintaining the block 8 in at least one position of adjustment. In the form shown, this resilient means is constituted by a leaf spring 14 of irregular shape that is curved upwardly to engage the under side of the block 8 intermediate its length and at either side of its point of engagement with the block said spring is curved downwardly to provide yieldable surfaces for frictional engagement with the side of the

channel bar 4, the opposite ends of the spring being bent upwardly into engagement with the ends of the block 8 to retain the spring in position. Each end of the spring 14 between its point of engagement with the block and its upwardly bent end is therefore of generally arcuate form 14^a and provides a yieldable catch which cooperates with the end of the lower side wall 4^b, 10 when it snaps past the same, to yieldingly maintain the block, and consequently the lid 2, in raised or adjusted position.

Operation.—The parts being in the position illustrated in Fig. 2, and it being desired to swing the lid or cover 2 to open position, it is only necessary to swing the front end of the lid upwardly and this movement is transmitted by bracket 12, link 10, and pivot pin 9 to the friction block 8, 20 moving the latter between the side walls of the channel bar 4 toward the rear end thereof. When in full open position the arcuate portion 14^a of the spring 14, due to the inherent resiliency of the latter, snaps past 25 the rear end of the lower side wall 4^b as is clearly indicated in Fig. 1. The lid is thus yieldingly maintained in open position. When it is desired to lower the lid 2, it is only necessary to press the same downwardly 30 by a slight pressure, whereupon spring 14 is compressed, and due to the curved surface of the portion 14^a of the spring, said portion is readily forced out of engagement with the end of the side wall 4^b, whereupon the block 35 8 moves to the right as viewed in Fig. 1. The friction between the block 8, spring 14, and the side walls of the channel bar 4, may be such as to hold the lid 2 at any point 40 of adjustment of the block 8 throughout the length of the channel bar 4, so that an extremely light pressure only is required to move the lid in either direction after the curved portion 14^a of the spring is forced 45 out of engagement with the end of the side wall 4^b, although it is evident that various positions of adjustment for the lid may be secured by providing suitable depressions, or by cutting suitable openings or interruptions in the wall of the channel bar 4. It 50 is therefore to be understood that the term “interruption” as hereinafter employed is generic to the end of the wall, a depression therein, or a suitable opening therein.

The lid or cover can be opened and closed 55 without noise and without the necessity of performing two operations or employing two hands. By cutting away the opposite ends of the wall 4^b as indicated at 4^c, the guide members, constituted by the plate 3 60 and channel bar 4, are interchangeable and may be used on either the right or the left hand side of the cabinet. The spring 14 is also reversible. The side walls of the channel bar 4 are shown as parallel one to the 65 other, but it will be understood that if de-

sired these side walls may slightly converge throughout their entire lengths, or a portion of the same. Various other changes may be made in the details of construction without departing from the invention as defined in 70 the following claims.

What is claimed is:—

1. A device of the class described comprising, in combination with a supporting body and a member mounted for movement relative to said body, a guide member having side walls one of which is shorter than the other, means slidably mounted between said walls and having frictional engagement therewith, a link secured to said first-named member and said means, and resilient means interposed between the first-named means and the short wall for engaging the end of said short wall to yieldingly hold said first-named member in adjusted position. 85

2. A device of the class described comprising, in combination with a supporting body and a member mounted for movement relative to said body, a guide member having upper and lower side walls, one wall being shorter in length than the other wall, a block slidably mounted between said walls, a link secured to said first-named member and said block, and a leaf spring, having an arcuate portion, interposed between the block and 90 shorter wall, said arcuate portion being adapted to engage an end of the shorter wall 95 to yieldingly hold said block in adjusted position.

3. A device of the class described comprising a channel member, a block slidably mounted between the walls of said member, supporting means operatively secured to said block, and a spring, having an arcuate portion, engaging the block and one of said 105 walls, the arcuate portion being adapted to have yielding engagement with one end of the last-named wall.

4. A one-hand lid support comprising, in combination with a cabinet and a lid therefor, a channel member having straight side walls secured to the cabinet, the lower of said walls being of a length different from the upper wall, means slidably mounted between said walls, means including a link 110 operatively secured to said first-named means and said lid, and resilient means movable with the first-named means and slidably engaging said lower wall, a portion of said last-named means being adapted to yieldingly engage an end of the lower wall. 115

5. A one-hand lid support comprising, in combination with a cabinet and a lid therefor, a channel member having walls of different lengths, means slidably mounted between said walls, means including a link operatively secured to said lid and first-named means, and resilient means movable with said first-named means and slidably engaging one of said walls, a portion of said 125 130

resilient means being adapted to engage an end of the last-named wall to yieldingly hold the lid in adjusted position.

6. A one-hand lid support comprising, in combination with a cabinet and a lid therefor, a pair of parallel walls secured to the cabinet, a member slidably mounted between said walls, means including a link operatively secured to said member and said lid, and resilient means between said member and one of said walls and normally held in compression therebetween but expansible into an interruption of said wall for yieldingly holding said member in adjusted position.
- 10 7. A one-hand lid support comprising, in combination with a cabinet and a lid therefor, a pair of walls secured to the cabinet, a member slidably mounted between said walls, means including a link operatively se-

cured to said member and said lid, and a leaf 20 spring between said member and one of said walls and normally held in compression therebetween but expansible into an interruption of said wall for yieldingly holding said member in adjusted position.

- 25 8. A device of the character wherein a supporting link is pivotally connected to a block slidable between a pair of walls and a resilient member is interposed between the block and one of said walls, characterized 30 by the fact that the resilient member is adapted to expand into an interruption of said wall to yieldingly hold the block in adjusted position.

In testimony whereof I have signed this 35 specification.

ALBERT E. LANE.
